UNITED STATES PATENT OFFICE.

GEORGE W. FRICK, OF SYRACUSE, NEW YORK.

APPARATUS FOR HANDLING NEWSPAPERS.

No. 856,460.

Specification of Letters Patent.

Patented June 11, 1907.

Application filed October 14, 1905. Serial No. 282,841

To all whom it may concern:

Be it known that I, GEORGE W. FRICK, of Syracuse, in the county of Onondaga, in the State of New York, have invented new and 5 useful Improvements in Apparatus for Handling Newspapers, of which the following, taken in connection with the accompanying drawings, is a full, clear, and exact description.

10 This invention relates to improvements in apparatus for handling newspapers as they are delivered from the press in bunches of fifty, more or less, and its essential purpose is to automatically convey these bunches of 15 papers from the press to some other locality or part of the building where it may be convenient to assort and distribute the papers to the salesagents. Heretofore it has been customary to employ a number of boys or men 20 for this purpose, and in many instances, the distributing room is located in the upper part of the building, which necessitates climbing several flights of stairs and renders the manual work extremely laborious and is attended 25 with more or less confusion, owing to the haste with which these papers are usually turned out.

It frequently becomes necessary in the installation of my apparatus to carry the papers 30 considerable distances in both vertical and horizontal planes, and a further object, therefore, of my invention is to so construct and adjust the cars and their guides or tracks that the papers will be held in a substantial 35 horizontal position on both the vertical and horizontal portions of the system.

It is evident from the foregoing description 40 that the apparatus involves a receiving station and a delivery station; an endless traveling belt or conveyer having paper-holding cars or carriers attached at intervals thereto, and suitable tracks or guides upon which the cars travel in transit from the receiving to the delivery stations.

45 In the drawings, Figure 1 is an elevation of my improved newspaper-handling apparatus or system in which the newspapers are carried vertically from the receiving station and are then carried horizontally, and finally 50 vertically to the delivery station where they are discharged automatically upon a suitable table, portions of the vertical and horizontal sections of the system being broken away. Fig. 2 is a perspective view of one of the detached cars for carrying the newspapers in

bundles or packages of fifty, more or less, from the receiving to the delivery station. Fig. 3 is a horizontal enlarged sectional view taken on line 3—3, Fig. 1. Figs. 4, 5 and 6 are detail views of the car and portions of the 60 track or guide, the car being shown in different positions assumed during its transit from the receiving to the delivery stations; Fig. 4 showing the car at the receiving station as just about to pick up a bunch of papers as delivered from the press, and Fig. 5 showing the car on the vertical rise leading from the delivery station, while Fig. 6 shows the position of the car while traveling from the vertical leg to the horizontal portion of the system. 65 Fig. 7 is a top plan of the upper terminal end or delivery station of the system, seen in Fig. 1. Fig. 8 is a sectional view taken on line 8—8—, Fig. 7. Fig. 9 is a top plan of the detached movable track section in the position 70 shown in Fig. 6 showing its supporting bearing and a portion of the track in section and also showing its counter weight.

In order that my improved apparatus may be understood in all of its possible adaptations 80 to meet the different conditions existing in different printing houses, I have shown means for conveying the papers vertically and horizontally through several turns, and as consisting essentially of a suitable supporting frame 85 —1—; outgoing tracks or guides —2—; return tracks or guides —3—, an endless chain-belt —4— traveling from the receiving to the delivery stations along the guides or tracks —2— and —3— and a series of cars —5— 90 which are attached at regular intervals to the chain belt —4—. This apparatus also includes a stationary newspaper supporting bed or table —6— at or near the receiving end of the system, and a second stationary 95 table or bed —7— at the delivery end of the system.

The stationary-bed or receiving table —6— is located in close proximity to the delivering end of a printing-press, a portion of which is 100 shown in Fig. 1, and indicated by the reference numeral —a—, the relative positions of such bed with the delivering end of the press being such that the bundles or bunches containing fifty more or less papers may be 105 discharged automatically and directly from the press upon the table —6—, although in some instances, it may not be practicable to install my apparatus so as to bring the bed —6— in such relative relation to the dis- 110

charge end of the press, and under such conditions it may be necessary to transfer the bundles or bunches of papers, by hand, from the press to the receiving-table —6—. This receiving-table —6— is preferably rigidly secured to and becomes a part of the main supporting-frame —1—, although it is projected forwardly some distance beyond one side, as the upwardly moving side of the traveling endless conveyer-belt —4— and its cars —5— and is usually provided with a series of arms —6'— which project inwardly from the front supporting-bar —8— and are spaced apart horizontally to permit similar arms —9— of the carriage —5— to travel between them for the purpose of lifting the bunch of papers from the upper surface of the bed or table —6— and carrying them upwardly and onwardly to the delivery station or terminal end of the carrying system.

The cars —5— are substantially identical, one with the other, and are, therefore, interchangeable, and each consists of the paper-supporting arms —9— and suitable back slats or abutments —10— forming continuations of, and at substantially right angles to the arms —9—. These arms —9— and —10— are secured at their junctions one with the other upon a cross-shaft or rod —11— and the upper ends of the back-pieces —10— are similarly connected to a second cross-shaft or rod —12—, while the arms —9— are spaced apart to receive the arms —6'— of the receiving bed or table —6— during the upward movement of the car.

Mounted upon the outer ends of the shafts or rods —11— and —12— are additional angle bars or brackets —13— which are disposed in substantially the same plane, and are of nearly the same form as the united bars —9— and —10—, thus binding the car or paper-supporting bed, said additional bars —13— being united or connected to the horizontal paper supporting bars —9— by additional comparatively short rods or shafts —14—, as best seen in Fig. 2.

Loosely mounted upon the opposite ends of each of the shafts —11— and —12— are suitable rollers —15— and —16— and the front ends of the horizontal portions of the bars —13— are provided with depending brackets —17— carrying rollers —18— which are similar to the rollers —15— and —16— and those at each end of the car are disposed in substantially the same vertical plane and are adapted to ride in the adjacent sides of the track or guide —2—, previously mentioned. It may, however, be mentioned here that at no time are more than two of the rollers on each side of the car in engagement with the track, and these are so arranged that when the car is traveling in a vertical direction, the rollers —15— and —16— at each side of the car are in engagement with their supporting guides or tracks so as to

support the car with the arms —9— in a substantially horizontal position, although in practice the outer ends of the bars —9— are inclined slightly above a horizontal plane for the purpose of better retaining the papers in operative position and causing them to work back against the back pieces —10— to constitute limiting stops.

The extreme outer ends of the shaft —11— are provided with suitable bearings —15'— having links —19— which constitute a part of the chain —4— and whereby each end of each car is attached to one of the endless chain-belts of which there are two, one at each side of the frame —1—. It therefore, follows that each track —2— and —3— is composed of opposite lengthwise guides just inside of the endless chain belt for receiving and guiding the rollers —15—, —16—, and 18 of the car.

Each of the opposite sides or rails of the track —2— is composed of parallel bars of angular cross section, the bars of each side of the track being arranged to form on its inner face, a lengthwise groove in which the rollers of the car travel and by which said car is supported with the arms —9— in a horizontal position while the car is in transit with a bunch of papers from the receiving bed or table —6— to the delivering bed or table, 95 presently described, at the upper terminal end of the system.

The endless chains or cables are mounted at the receiving end or station upon suitable sprocket-wheels —20— and are similarly supported at the delivery station upon additional sprocket-wheels —21—, the intermediate portions of said chain-belts being supported at the turns by suitable idlers, as sprocket-wheels —22— and —23—.

The sprocket-wheels —20— are mounted upon a driving shaft —24— below the receiving bed —6— so as to permit the arms —9— of the cars 5 to assume a substantially horizontally position before reaching the table 115 on their upward movement, whereby the bunches or bundles of paper are lifted bodily from the upper surface of said table as the arms —9— of the car pass upwardly between the similar arms of the table —6—. The shaft —24—, and therefore, the sprocket —20— and endless chain belts —4— are driven through the medium of a driving shaft —25— and worm —26—, meshing with a worm-gear —27—, as best seen in Fig. 1.

The guides or tracks for the outgoing cars, and those for the incoming cars are tied together at intervals by cross straps or braces —28—, which in turn, are secured to the main supporting frame —1—, and this main frame is suitably sustained in the building, as —B—, in a manner best seen in Fig. 1, which represents one of the floors of the building.

It will be observed upon reference to Fig. 1, in which the cars are shown in different posi-

tions, that when the cars are traveling upwardly along the vertical portions of the track, the rollers —15— and —16— are engaged with the track while the other rollers —18— at the outer ends of the arms —9— are free and project outwardly from the track, but when these cars reach the horizontal portions of the track the rollers —15— and —18— are guided therein and the upper rollers —10— are free and project some distance above the outgoing track. The object of this is to maintain the paper-supporting arms —9— in a substantially horizontal position, although in practice, I prefer to support the rollers —18— at a greater distance beneath the arms —9— than the inner rollers —15— so that when the car is traveling along the horizontal portion of the track from the receiving to the delivery station, the arms —9— will be held in a position slightly inclined from a horizontal plane with the free trailing ends highest so that the jolting or jar upon the car while in transit from the receiving to the delivery station will tend to work the papers backwardly against the back pieces or abutments —10— rather than toward the open side of the car.

In order that the car may be maintained in the position just described while traveling along the vertical and horizontal portions of the track in transit from the receiving to the delivery station, I provide such track with an inwardly swinging section —30— which is located near the junction of the upright with the horizontal portions of the track and is normally held in its upright position by a counter-weight —31— to form a continuation of such track at the turn, but is adapted to be engaged and rocked inwardly, as best seen in Fig. 6, by the rollers —18— of each car as it is drawn from the vertical to the horizontal track or guide by the chain belts —4—, such car being steadied or maintained in operative position during such turn by the engagement of the rollers —16— with a track extension —32— projecting upwardly from the upper end of the swinging track section —30—.

The inner rail or bar of the track —2— is continuous around the turn at the junction of the upright with the horizontal positions of said track and is concentric with the axis of the idlers —23— for the chain —4—, and inasmuch as the shaft for the rollers —15— at the center of the car is attached directly to the chain belts —4— it is clear that the cars will be drawn concentrically around the axis of the idlers —23— and that the guides or grooves of the vertical and horizontal portions of the track —2— are substantially tangential to the periphery of the sprocket-wheel —23— so as to cause the rollers —15— to ride, usually from the vertical to the horizontal portions of said track while the car is in transit from the receiving to the delivery station.

During this turn the weight of the bundle of papers upon the arms —9— tends to tilt the upper portion of the car forwardly, and to prevent this, I provide the extension —32— which rises in a suitable curve upwardly and rearwardly above the horizontal portion of the track so as to form a bearing for the rollers —16— to hold the car with its arms —9— in a substantially horizontal position until the rollers —15— and 18— enter the horizontal portions of the track, thus relieving the rollers —16— from further work until the car starts to enter another vertical portion of the track. During this transfer of the car from the vertical to the horizontal portion of the track the switch or movable section —30— is operated in the manner previously described to partially sustain the weighted end of the car and to guide the rollers —18— into the adjacent end of the horizontal track, and as soon as the rollers —18— are properly entered into said horizontal track sufficient to free the swinging track-section —30— the latter are returned to their normal upright positions by the weights —31—, and are therefore, in position to receive and guide the upper rollers —16— of the next advancing car, it being understood that the end of the upper guide-rail of the horizontal portion of the track adjacent to the sprocket-wheel —23— terminates a sufficient distance inside of the upper end of the adjacent outer vertical rail or swinging section —30— to permit the rollers —16— to pass upwardly through the intervening space, and along the extension —32—. In like manner, the opposite end of the same upper horizontal rail terminates some distance inside of the axis of the idlers —22— and the outer rail of the adjacent upright section of the track is also terminated some distance above said axis sufficient to allow the upper rollers —16— of the car to travel under the lower end of the adjacent upright outer rail so as to permit the rollers —16— and —15— to successively enter the grooves of this upright portion of the track —2— during the transit of the car to the delivery station, the inner rail of the same track being continuous around the turn from the horizontal to the second upright so as to form a continuous guide for the rollers —15—. It is now evident that as the car enters the second upright section of the track the rollers —15— and —16— are guided therein, while the other rollers —18— are free. As the loaded car continues along the upright, it is, of course, carried around the periphery of the sprocket-wheels —21— by the chain-belt —4— and the upper end of said upright is provided with a semi-circular extension —33— performing the same function as the extension —32— and is also provided with a switch or movable track section —34—, Figs. 1 and 8, having a counter-weight —35— for

- holding it normally in an upright position, said swinging section —34— and its counter-weight —35— being substantially the same as the swinging section —30— and its counter-weight —31— and they perform the same function in guiding the car in its turn from a vertical to a horizontal course as it travels around the sprocket —21— at the delivery station.
- 10 A stationary bed or table —7— similar to the bed or table —6— is supported between and within the circular plane of the periphery of the sprocket-wheels —21— at the delivery station upon suitable uprights —41—, which, in turn, are adjustably mounted upon a transverse bar —42— forming a part of the main supporting frame and upon which the sprocket-wheels —21— are journaled. This bed or table —7— is adapted to receive 15 the bundles or bunches of newspapers from the cars —5—, as they are successively brought to the delivering station and carried around the periphery of the sprocket-wheels —21—, said bed or table being provided with a series of horizontally projecting arms —7— between which the arms —9— of each car pass while making the turn around the sprocket-wheels —21— so that the bunches of newspapers on each car are successively 20 deposited upon the arms —7— of the bed or table —7— and in order that these bundles may not accumulate upon the bed —7—, I provide each car with depending arms —10— which project below the upper surface of the bed —7— and travel lengthwise of and between the arms —7—, as best seen in Fig. 8.
- It will be seen upon reference to the drawings that the arms —10— move in advance of the upper supporting arms —9— so that 25 the papers which may rest upon the bed —7— are engaged by the arms 10— and are moved along the arms —7— upon an auxiliary bed —45—, as best seen in Figs. 1, 7 and 8. This auxiliary bed is composed of a fixed table —46— and sliding arms —47—, the table —46— being mounted upon the frame —1— of the apparatus and is provided with suitable guide-openings in which the arms —47— are movable. These arms —47— are disposed in a horizontal position and correspond 30 in number and are aligned with the dependent arms —10— of the cars —5— and their inner ends are provided with rollers which are engaged by the pendent arms —10— as each car advances around the turn at the receiving station. It is now obvious that 35 these pendent arms 10— advance between the arms —7— of the table —7— and the bunch of papers previously deposited upon said bed or table —7— are engaged and moved by the pendent arms 10— onto the sliding bars —47— and during such movement of the bunch of papers the lower ends of the fingers or arms 10— encounter the ends, 40 or rather the rollers on the ends of the bars —47— and force the same outwardly or endwise in their guides in the table —46— against the action of the counter-weight —48— or equivalent device whereby the arms —47— are returned to their normal position when the pressure upon the ends or rollers of the arms —47— is relieved by the continued movement of the cars —5— around the drum —21— on the return after depositing the bunch of papers from the car upon the table —7—.
- 45 A section of the inner rail of the track, beginning at a point just below the switch or swinging arm —34— to a point in a vertical line directly above the axis of the drum —21— is removed to allow the arms —34— and rollers —18— to move inwardly as the upper rollers —16— enter the track or guide-groove on the return, or rather just before the depositing of the papers from the car upon the bed —7—. In order that the intermediate rollers —15— of the car may enter the track or guide-grooves upon the beginning of the return movement of the empty cars or about the time the papers are deposited upon the table —7—, a section —50— of the inner rail at the rear of the drum —21— is hinged at —51— to swing outwardly a sufficient distance to allow the entrance of the rollers —15— into the underlying grooves of the track.
- 50 I have now described the mechanism for transporting the papers from the press or receiving station to a remote terminal station or place of delivery, as the tables —7— and —46—, upon which latter table the papers are finally deposited and are then distributed by hand in the desired quantities to the distributing or sales-agents.
- It will be observed that the cars are maintained in substantially the same position, that is, with their open sides facing in substantially the same direction while moving along the outgoing track or guide from the receiving bed —6— to the delivery bed —7— and continue in this same position on the return along the vertical legs of the return track so that the arms —9— of the empty cars travel inside of the chain belt on the return from the delivery to the receiving station, and inasmuch as the cars are empty the rollers —15— and —16— are allowed to remain in traveling engagement with the horizontal portions of the return track —3—, as best seen in Fig. 1.
- 55 As the empty cars return to the receiving station and travel around the drum —20— the rollers —18— on the free ends of the arms —9— follow by gravity upon an underlying inclined track or rest —55— which holds the arms —10— in a substantially upright position, although slightly inclined forwardly so that the rollers —16— will readily encounter and enter the lower end of the track —2—; the lower ends of the outer ends 125

of said track being projected downwardly some distance beyond the lower end of the inner rails to encounter the rollers —16— and facilitate their entrance into the lower 5 ends of the guides or track —2—, it being understood that both sets of rollers —15— and 16— enter the lower ends of the guides or track —2— to hold the arms —9— in a substantially horizontal position while traveling upwardly between the arms —6— of the receiving table —6—, as previously described.

In order that the invention may be thoroughly understood, the action of the apparatus may be briefly described as follows: The newspapers in bunches or bundles of 50, more or less, are deposited from the press —a— either automatically or by hand upon the table —6— from which they are lifted 10 by the upward movement of one of the cars —5— which is actuated by the endless belts or chains —4— and is guided in the present instance, along the vertical portion of the track —2— leading from the bed —6—, such 15 loaded car being then transferred onto the horizontal portion of the same track, as best seen in Fig. 1, and in order to make this transfer possible a section —30— of the outer rail of the track —2— is made to swing 20 by the upward movement of one of the cars —5— which is actuated by the endless belts or chains —4— and is guided in the present instance, along the vertical portion of the track —2— leading from the bed —6—, such 25 loaded car being then transferred onto the horizontal portion of the same track, as best seen in Fig. 1, and in order to make this transfer possible a section —30— of the outer rail of the track —2— is made to swing 30 inwardly and downwardly against the action of the counter-weight —31—, said swinging section serving, when in its normal position, as a continuation of the track to guide the roller —16— until it reaches and is further 35 guided by the extension —32—, such extension serving to hold the arms —9— in a substantially horizontal position against the weight of the papers thereon until the car is advanced sufficient to enter the rollers in the 40 adjacent end of the horizontal portion of the track —2— and as the car continues to move along said horizontal track the rollers —18— encounter the swinging track-section —30—, which supports the adjacent end of the car 45 until said rollers —18— also enter the adjacent end of the horizontal portion of the track, the counter-weight —31— serving to return the track-section —30— to its normal upright position as soon as the rollers 15— and 18— are positively entered upon the 50 horizontal outgoing track. As the loaded car leaves the horizontal outgoing track the rollers —16— and 15— enter the upright leg of the track on its way to the delivery station or table —7—, such car being drawn 55 from the front side of the table upwardly above and lengthwise of the table —7— and is then drawn downwardly by the chain-belts —4— causing the arms —9— upon 60 which the bundles of papers rest to travel between the arms —7—, thereby depositing the bundle of papers from the car upon the arms —7— and the bunch of papers which was previously left upon the arms —7— by 65 the next preceding car are engaged by the

pendent arms —10— and move along said arms —7— and upon the sliding bars —47—. As the loaded car continues its forward movement above the table —7— the arms 10— encounter the rollers on the ends of the bars 70 —47— upon which a bunch of papers were previously deposited and forces said bars —47— outwardly and across the underside of the table —46—, causing the bundle of papers on the bars —47— to ride upon said 75 stationary table —46— from which they may be removed by hand. As soon as the loaded car has deposited its papers upon the arms —7— of the table —7— its rollers 80 15— engage and swing the track sections 80 —50— outwardly, thus permitting said rollers to enter the return guides of the track —3—, in which position the cars are returned to the place of starting and the bars —47— are returned to their normal position seen in 85 Fig. 8 by the counterweight —48— as soon as the car has passed the swinging sections —50—. In order that the chain belts may be tightened when necessary to take up any slack, the shaft upon which the drums —21— 90 are journaled is supported in vertically adjustable boxes —60—, which are adjusted and held in place by suitable screws —61—, Figs. 1 to 8.

What I claim:

1. In an apparatus for handling newspapers, a track having portions thereof disposed at an angle to each other and provided with a swinging section near said angle, an endless conveyer traveling along said track, and a car attached to the conveyer and provided with bearings riding on said track, one of the bearings operating to tilt and to ride upon the swinging track section when the car is turning the angle. 95

2. An apparatus for handling newspapers comprising receiving and delivery stations, a table at the receiving station having a plurality of arms spaced apart for supporting a bunch of papers, an endless belt traveling 100 from one station to the other and return, cars attached at intervals to the belt and having portions thereof traveling between said arms a movable support receiving the papers from the cars at the delivery station, and means 105 on the belt for actuating said support as the papers are deposited thereon.

3. In an apparatus for handling newspapers, a track having upright and horizontally extending portions, an endless, conveyer belt 110 traveling along said track, a car having a bottom and back disposed at an angle to each other, said car being pivotally attached to the conveyer at the junction of said bottom and back, bearings on the bottom and back 115 of the car, and additional bearings on the center of the car, the central and back bearings riding in the upright portions, and the central and bottom portions riding in the horizontally extending portions of the track. 125

130

4. In an apparatus for handling newspapers, a track having upright and horizontally extending portions, an endless conveyer belt traveling along said track, a car pivotally attached to said conveyer and provided with horizontal arms spaced apart and forming the bottom, said car having upright arms rigidly connected to the horizontal arms and forming the back of the car, and a system of roller bearings on the bottom, back and at the junction of the bottom with the back of the car and adapted to ride on said track to keep the car in operative position to carry its load.
5. In a newspaper handling apparatus, a track, an endless conveyer traveling along said track, a rod attached to said conveyer, angle bars mounted on the rod and a system of roller bearings mounted on the rod and angle bars respectively some distance apart and riding on said track.
6. In an apparatus for handling newspapers, a track having an upright portion and a horizontal portion, an endless conveyer running along the track, a paper supporting car attached to and moving with the conveyer, said car having a horizontal bottom and an upright back, bearings on the back engaging the upright portion of the track to hold the bottom of the car horizontally while traveling vertically, and additional bearings on the bottom to engage the horizontal portion of the track for holding the bottom horizontally while traveling along said horizontal portion of the track, and means for engaging said bearings and holding the car with its bottom in a horizontal position while passing from the upright to the horizontal portions of the track.
7. In an apparatus for handling newspapers, a track having an upright portion and a horizontal portion, said track having a movable section at the junction of the upright with the horizontal portion, an endless conveyer traveling along said track, a paper supporting car attached to and moving with the conveyer along said track, said car having a horizontal bottom and an upright back, separate bearings on the bottom and back of the car, the movable section of the track being normally aligned with the upright portion of the track to engage the bearing on the back of the car for holding said car with its bottom in a horizontal position while traveling from the upright to the horizontal portion of the track, said movable section being also engaged and moved from its normal position by the bearing on the bottom of the car to cause the latter bearing to travel from the upright into the horizontal portion of the track.
8. In an apparatus of the class described, an endless conveyer and its supporting drums, portions of the conveyer being supported in horizontal planes, means for transmitting motion to the conveyer, guides following the line of travel of the conveyer, the outgoing guide having a swinging section at the junction of the vertical with the horizontal portion of the guide, paper-carrying cars attached to the conveyer and guided in said guides, and means on each car for engaging and swinging the movable section of the guide as the car travels from the vertical to the horizontal portion of the guide, said movable guide-section normally forming a guide for a portion of the car when entering the horizontal portion of the guide, and means to support the papers in the path of the moving cars.
9. In an apparatus of the class described, an endless conveyer and its supporting drums, means for transmitting motion to one of the drums, paper-carriers attached to the conveyer, means for supporting the papers in the path of said carriers, a paper-supporting table in proximity to the delivery terminal of the conveyer and located in the path of the carriers, whereby the papers on the carriers are deposited on said table, and means on each carrier for engaging and forcing the papers from said table.
10. In an apparatus of the class described, an endless conveyer and its supporting drums, means for transmitting motion to one of the drums, paper-carriers attached to the conveyer, means for supporting the papers in the path of said carriers, whereby the papers on the carriers are deposited on the table, means on each carrier for engaging and forcing the papers from said table, additional means for receiving the papers discharged from the table, said additional means being actuated by the carrier away from the table, and means to return the last named means to its normal position.
11. In an apparatus of the class described, an endless conveyer and rotary supports therefor, one at the receiving station and one at the delivery station, paper-supporting arms attached to the conveyer and spaced apart, means for holding said arms in a substantially horizontal position during their transit from the receiving to the delivery station, additional means for supporting the papers in the path of said arms, stationary arms at the delivery station arranged in a plane intersecting the path of the traveling conveyer arms, whereby said conveyer arms are caused to travel past the stationary arms to transfer their papers upon said stationary arms, sliding bars movable relatively to the stationary arms, means on the traveling paper carriers for engaging and forcing the papers from the stationary arms onto the sliding bars and for engaging and actuating said sliding bars away from the stationary arms, and additional means for automatically returning the sliding bars to their normal positions.
12. In an apparatus of the class described,

an endless conveyer and paper-carrying cars attached thereto, and each provided with substantially horizontal arms spaced apart, a stationary table also having arms spaced apart, the arms of the cars moving between the arms of the stationary table, a second stationary table, sliding bars between said tables and means on each car to force the papers from the first named table onto the

sliding bars, and for actuating said bars to transfer the papers therefrom onto the second stationary table.

In witness whereof I have hereunto set my hand this 25th day of September 1905.

GEORGE W. FRICK.
